(57) **CLAIM**

The ornamental design for a bottle, as shown and described.

DESCRIPTION

FIG. 1 is a top perspective view of a first embodiment of a bottle illustrating our design;

FIG. 2 is a front view of the bottle shown in FIG. 1;

FIG. 3 is a back view of the bottle shown in FIG. 1;

FIG. 4 is a left side view of the bottle shown in FIG. 1;

FIG. 5 is a right side view of the bottle shown in FIG. 1;

FIG. 6 is a top view of the bottle shown in FIG. 1;

FIG. 7 is a bottom view of the bottle shown in FIG. 1;

FIG. 8 is a top perspective view of a second embodiment of a bottle illustrating our design that differs from the first embodiment of FIGS. 1–7 in that the cap is shown in dashed lines, otherwise the design of the bottle is the same as the first embodiment;

FIG. 9 is a top perspective view of a third embodiment of a bottle illustrating our design;

FIG. 10 is a front view of the bottle shown in FIG. 9;

FIG. 11 is a back view of the bottle shown in FIG. 9;

FIG. 12 is a left side view of the bottle shown in FIG. 9;

FIG. 13 is a right side view of the bottle shown in FIG. 9;

FIG. 14 is a top view of the bottle shown in FIG. 9;

FIG. 15 is a bottom view of the bottle shown in FIG. 9; and, FIG. 16 is a top perspective view of a fourth embodiment of a bottle illustrating our design that differs from the third embodiment of FIGS. 9–15 in that the cap is shown in dashed lines, otherwise the design of the bottle is the same as the third embodiment.

The dashed lines in FIGS. 8 and 16 form no part of the claimed design. All other surfaces and portions of the bottle in FIGS. 1–16 not shown in the figures or otherwise described in the specification form no part of the claimed design.
